UNITED STATES PATENT OFFICE.

CHARLES R. CHENERY, OF BUFFALO, NEW YORK.

HAT-BOX.

1,297,442.

Specification of Letters Patent. Patented Mar. 18, 1919.

Application filed March 23, 1917. Serial No. 157,036.

To all whom it may concern:

Be it known that I, CHARLES R. CHENERY, a citizen of the United States, residing at Buffalo, in the county of Erie and State of New York, have invented certain new and useful Improvements in Hat-Boxes; and I do hereby declare the following to be a full, clear, and exact description of the invention, such as will enable others skilled in the art 10 to which it appertains to make and use the same.

This invention relates to a hat box and has for one of its objects the provision of a device of this character, whereby the hat may be readily inserted and removed through the front wall of the device and also having means whereby accessories used in connection with the hat may be readily stored when not in use.

Another object of this invention is to provide a receptacle having a door way in the front wall adapted to be closed by a hinged door providing means whereby the hat may be readily inserted and removed from the receptacle through the door way without removing the receptacle from a shelf or like place or of supporting other articles.

Another object of this invention is the provision of longitudinally extending guide blocks secured to the side and bottom walls of the receptacle adapted to slidably receive a drawer, which blocks support a false bottom and also reinforce the bottom wall of the receptacle.

A further object of this invention is the provision of strips disposed about the door way adapted to engage the door to form a dust-proof closure and which rests upon the false bottom preventing said false bottom 40 from disengaging from the guide blocks.

A further object of this invention is to provide each of the walls of the receptacle construction of upper and lower sections which are hinged together for the purpose of 45 permitting the walls to be folded inwardly upon each other to render a compact article what will occupy a considerably small space when shipped.

A further object of this invention is the provision of means carried by the top wall 50 of the receptacle and adapted to be inserted within slots in the side and rear walls for the purpose of holding the walls in assembled position.

A still further object of this invention is the provision of a hat box of the above stated

character, which shall be simple, durable and efficient, and which may be manufactured and sold at a comparatively low cost.

With these and other objects in view, as 60 will become more apparent as the description proceeds, the invention consists of certain novel features of construction, combination and arrangement of parts as will be herein-after more fully described and claimed. 65

For a complete understanding of my invention, reference is to be had to the following description and accompanying drawing, in which:

Figure 1 is a perspective view of a hat 70 box constructed in accordance with my invention,

Fig. 2 is a front elevation of the same, illustrating the door in an open position,

Fig. 3 is a vertical sectional view illus- 75 trating the manner of mounting the drawer in the receptacle,

Fig. 4 is a transverse sectional view illustrating the guides for receiving the drawer,

Fig. 5 is a fragmentary sectional view 80 illustrating the receptacle with the drawer removed,

Fig. 6 is an end elevation of the device in a folded position,

Fig. 7 is a sectional view taken on the 85 line 7—7 of Fig. 6.

Referring in detail to the drawings, the numeral 1 indicates a substantially rectangular receptacle having the front wall 2 thereof provided with a door way 3, which is 90 adapted to be closed by a door 4. The door 4 has a piece of fabric 5 secured thereto which is in turn secured to the wall 2, whereby the door is hinged so that the same may be readily swung in an open or closed position. A plate 6 is secured to the free end of the door and has pivoted thereto, a lever 7, which is adapted to engage a catch 8 carried by the wall 2 of the door, whereby the door is locked in a closed position. 100

Relatively spaced and longitudinally extending guide members 9 are positioned upon the bottom wall of the receptacle 1 and have their ends abut the rear and front wall 2 of the receptacle. Supported upon the guide 105 members 9 is a false bottom 10, forming a drawer space 11, in which is slidable a drawer 12. The walls of the drawer 12 are of such a height that the upper edges thereof will frictionally engage the under face of 110 the false bottom 10 when the drawer is slid inwardly and outwardly of the receptacle,

- thus providing means whereby the drawer will be held from accidentally sliding from the receptacle when being moved from one point to another.
- 5 Surrounding the door way 3 are dust strips 13, the side ones of which have their lower ends resting upon the false bottom 10, whereby the false bottom is held upon the guide members 9. The strips 13 are secured to the front wall 2. When the door 4 is in a closed position, the same abuts the dust strips 13, thus establishing a dust-proof door which will prevent any dust from entering the interior of the receptacle. Secured upon 15 the inner face of the door 4 is a frame 14, adapted to support a mirror 15. The frame 14 engages the dust strips 13 or the outer edges thereof when the door is swung to a closed position, further forming a dust-proof 20 connection between the door and the receptacle.

The front, rear and side walls 2, 2' and 3' are each constructed of upper and lower sections. The lower sections of each of the 25 walls terminating approximately in horizontal alignment with the false bottom 10. The upper sections are hinged to the lower sections by strips of tape 16 so that they may be folded inwardly over the false bottom when desired. The dust-proof strips 13 of the front wall 2 are also hinged as 30 illustrated at 17 for permitting the front wall 2 to fold inwardly over the false bottom 10. A cover or top 18 is hinged to the 35 upper edge of the upper section of the front wall 2 as shown at 19. Formed upon the side and rear edges of the top or cover 18 are attaching tabs 20 which have enlarged heads formed thereon that are adapted to 40 be inserted within the slots 21 formed in the side and rear walls of the receptacle for detachably securing the said walls of the top or cover 18 when desiring to fold the receptacle or box 1. The tabs 20 are re- 45 moved from the slots 21 and the cover is folded downwardly upon its hinge 19, the front wall 2 is then folded inwardly over the false bottom 10 having the cover or top 18 disposed between the false bottom 10 and

the cover or top 18. The side walls 3' are 50 then folded inwardly over the front wall 2 and later the rear wall 2' is folded inwardly over the side walls 3' providing a compact article as shown in Figs. 6 and 7.

If for some reason it is desired to make 55 a rigid box or receptacle after the same has been shipped, adhesive tape or the like may be placed over the hinges or the side and rear walls and upon the outer faces thereof.

From the foregoing description taken in 60 connection with the accompanying drawings, it will be noted that a dust-proof receptacle has been provided wherein a hat may be readily stored and also which is provided with a drawer that may be withdrawn from 65 the receptacle to receive accessories that are used in connection with the hat, such as hat pins, veils and the like.

While I have shown and described the preferred embodiment of my invention, it 70 will be understood that minor changes in construction, combination and arrangement of parts may be made without departing from the spirit and scope of the invention as claimed.

75 What is claimed is:

A folding hat box comprising side, front and rear and bottom and top walls, each consisting of upper and lower sections, the lower sections of the walls being permanently secured together, means for hinging the upper sections of the walls to the lower sections, said front wall having a door way, a hinged door closing said door way, means for hinging the top wall to the upper edge 85 of the front wall, said side and rear walls having slots adjacent their upper edges, and tabs formed upon the side and rear edges of the top wall adapted to be inserted in the slots to detachably secure the top wall to 90 the rear and side walls.

In testimony whereof I affix my signature in presence of two witnesses.

CHARLES R. CHENERY.
